Primary Examiner — Cynthia R Underwood*(74) Attorney, Agent, or Firm* — Cochran Freund & Young LLC; William W. Cochran(57) **CLAIM**

The ornamental design for a round floor grommet, as shown and described.

DESCRIPTION

FIG. 1 is a top isometric view of a round floor grommet showing my design.

FIG. 2 is a bottom isometric view of the round floor grommet.

FIG. 3 is a top view of the round floor grommet.

FIG. 4 is a bottom view of the round floor grommet.

FIG. 5 is a front view of the round floor grommet.

FIG. 6 is a back view of the round floor grommet.

FIG. 7 is a right side view of the round floor grommet; and, FIG. 8 is a left side view of the round floor grommet.

1 Claim, 8 Drawing Sheets(56)
